UNITED STATES PATENT OFFICE.

THOMAS B. ATTERBURY, OF PITTSBURG, PENNSYLVANIA.

APPARATUS FOR ORNAMENTING OPEN-ENDED GLASSWARE.

SPECIFICATION forming part of Letters Patent No. 406,693, dated July 9, 1889.

Application filed March 12, 1889. Serial No. 302,958. (No model.)

To all whom it may concern:

Be it known that I, THOMAS B. ATTERBURY, a citizen of the United States, residing at Pittsburgh, in the county of Allegheny and State of Pennsylvania, have invented new and useful Improvements in Apparatus for Ornamenting Open-Ended Glassware; and I do hereby declare the following to be a full, clear, and exact description of said invention, reference 5 being had to the accompanying drawings, and to the letters or figures of reference marked thereon, which form a part of this specification.

The invention relates to an improved device for ornamenting open-ended glassware, such as hand-blown lamp chimneys, shades, globes, &c.

The object of my invention is to construct a device by which I am enabled to ornament 15 lamp-chimneys, lamp-shades, &c., with various ornaments in depression or relief, as well as to give to the same irregular forms in the way of moldings, flutings, and the like, which has heretofore been found impracticable.

25 The invention consists in a novel construction of former having the ornamental configuration to be given to the article formed or cut in the inner face thereof, and a plunger or movable bottom to give to the article a flaring or fluted edge, and with a blow-snap to hold the article and permit the same to be blown to fill the still plastic glass into the 30 ornamented portion of the former.

In the accompanying drawings, Figure 1 is 35 a transverse section of the former, showing a lamp-chimney held by a blow-snap, and showing the movable bottom to the former to give the ornamental configuration to the top of the article. Fig. 2 is a plan or top view of 40 one form of movable bottom. Fig. 3 is a view of a lamp-chimney ornamented with the form of holder shown in Fig. 1.

A suitable frame A has mounted thereon a divided former B, having on its inner face 45 the ornamental configuration it is desired to give to the article, and which can be in any desired form to give to the article any desired ornamentation in depression or relief, and which former is provided with an open 50 end, as shown at B', to accommodate the size of the article. This former B' is shown as

made in two parts divided vertically and hinged or otherwise joined at one side and having a suitable catch or holder at the other. The former may, however, consist of two or 55 more jaws to close in on the article, if found desirable.

The lower end of the former B is made flaring and is fluted or corrugated to give to the end of the article the flaring corrugated form, 60 as shown at C.

The former B above the contracted end of the fluted portion is provided with a depressed ornamented portion D, (shown in this instance as made in concave form, with diagonally-arranged flutes to give to the article a convex fluted ornamental surface, and showing one form of ornamentation that may be given to the article. The plug, plunger, or movable bottom E is made in cylindrical form, with 65 its upper end made tapering, and with said tapering portion fluted or corrugated to correspond to the fluted or corrugated portion of the former B, and in connection therewith to give to the end or top of the article the flaring corrugated form. The plug or plunger moves or plays in a suitable guideway in the frame, and is operated by a foot-lever F, but 70 may be operated in any preferred way.

If desired, the plug or plunger may be connected to act in connection with the former or mold by the same lever.

As has before been stated, any desired ornamentation may be given to the former, and the same may be made of any desired length 85 to ornament more or less of the article.

The operation of the device is as follows: The article having been given its desired shape "by hand"—as, for instance, a lamp-chimney, as shown—the same is connected to 90 the blow-snap and the end inserted in the "glory-hole" to reheat it. The end is then placed in the enlarged end of the former and thrust down upon the plug or plunger, to which the pressure is then applied, which will 95 expand the end of the chimney and give to the same the flaring fluted form, substantially as shown in Fig. 3. This will form an airtight joint at this end, and then by blowing into the opposite end the article will be forced 100 out or expanded into the ornamented portion of the mold.

In an application filed by me of even date herewith, Serial No. 302,957, I have claimed the method of ornamenting glass articles, and such I do not claim in this application.

5 Having now described my invention, what I claim, and desire to secure by Letters Patent, is—

1. In a device for ornamenting hand-blown glassware, a former or mold having the ornamental configuration to be given to the article formed or cut in the inner face thereof, a plug to close the bottom thereof, and a device for holding the article and permitting the same to be blown to fill the still plastic 15 glass into the ornamented portion of the former, as set forth.

2. In a device for ornamenting hand-blown glassware, a former or mold having the ornamental configuration to be given to the article formed or cut in the inner face thereof, a 20 plug or plunger provided with the corrugated face to crimp the edge of the article, and a blow-snap to hold the article, substantially as and for the purpose set forth.

In testimony whereof I affix my signature in 25 the presence of two subscribing witnesses.

THOMAS B. ATTERBURY.
